[57] CLAIM

The ornamental design for a combined key holder and light, as shown and described.

DESCRIPTION

FIG. 1 is a perspective view of a combined key holder and light showing my new design, the dotted line showing of a key and chain being for illustrative purposes only;

FIG. 2 is a right side elevational view thereof;

FIG. 3 is a left side elevational view;

FIG. 4 is a front elevational view;

FIG. 5 is a rear elevational view;

FIG. 6 is a bottom plan view; and

FIG. 7 is a top plan view.
